(57) **CLAIM**

The ornamental design for a cork cage, as shown and described in the figures.

DESCRIPTION

FIG. 1 is a perspective view of a cork cage of the present invention, labeled for ease of orientation of the various drawings with the view designations. The cork cage is a metal frame with a plurality of decorative orbs mounted along the sides of the cage.

FIG. 2 is a plan elevational view of the front side of the cork cage of FIG. 1.

FIG. 3 is a side view of the right side of the cork cage of FIG. 1.

FIG. 4 is a top view of the cork cage of FIG. 1.

FIG. 5 is a side view of the left side of the cork cage of FIG. 1.

FIG. 6 is a plan elevational view of the back side of the cork cage of FIG. 1; and,

FIG. 7 is a bottom view of the cork cage of FIG. 1.
